US0D1028843S

(12) **United States Design Patent** (10) **Patent No.:** **US D1,028,843 S**
(45) **Date of Patent:** **** May 28, 2024**

(54) **SUPPORT**

(71) **Applicant:** **Autel Intelligent Technology Corp., Ltd.**, Shenzhen (CN)

(72) **Inventors:** **Yongshuai Wang**, Guangdong (CN); **Yuelong Liao**, Guangdong (CN)

(73) **Assignee:** **AUTEL INTELLIGENT TECHNOLOGY CORP., LTD.**, Shenzhen (CN)

(**) **Term:** **15 Years**

(21) **Appl. No.:** **29/812,366**

(22) **Filed:** **Oct. 20, 2021**

(30) **Foreign Application Priority Data**

May 18, 2021 (CN) 202130297751.5

(51) **LOC (14) Cl.** **12-16**

(52) **U.S. Cl.**

USPC **D12/223**; D8/354

(58) **Field of Classification Search**

USPC D8/349, 354, 355, 364, 366, 373, 380;

D10/49; D12/223; D14/388

CPC B60G 17/019; B60G 2204/1162; B60G

99/002; B60D 1/58

See application file for complete search history.

(57) **CLAIM**

We claim the ornamental design for a support, as shown and described.

DESCRIPTION

FIG. 1 is a front perspective view of a support showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the support in which the design is embodied that form no part of the claimed design.

1 Claim, 8 Drawing Sheets
